UNITED STATES PATENT OFFICE.

HIRAM W. HAYDEN, OF WATERBURY, CONNECTICUT, ASSIGNOR TO
HOLMES, BOOTH & HAYDENS, OF SAME PLACE.

LAMP BURNER AND CHIMNEY.

SPECIFICATION forming part of Letters Patent No. 225,929, dated March 30, 1880.

Application filed July 7, 1879.

To all whom it may concern:

Be it known that I, HIRAM W. HAYDEN, of Waterbury, in the State of Connecticut, have invented an Improvement in Lamps, of which 5 the following is a specification.

Lamp-burners have been made with a wick-tube guide, to which the upper part of the burner was connected, so that it could be removed from the wick-tube or replaced thereon. The 10 wick-tube has also been made so as to pass a broad wick through the reservoir-collar in a bent or folded condition. Chimneys have also been made with a flattened bulb and circular base, and also with an elliptical base and bulb, 15 and burners have been made with an elliptical chimney-holder, and also with an oblong chimney-holder and deflector.

The object of my present invention is to render the action of the air more uniform on the 20 flattened flame than heretofore, and to provide for the heat and expansion of the burner and chimney being nearly uniform throughout, and at the same time the parts of the burner can be separated with facility for lighting or 25 cleaning, and when the chimney-holder and chimney are removed they will stand firmly on their flat base.

In the drawings, Figure 1 is a vertical section of the lamp burner and chimney complete. 30 Fig. 2 is a plan at the line $\alpha\alpha$ of the chimney. Fig. 3 is a plan of the chimney-holder and deflector, and Fig. 4 is an inverted plan of the screw-base of the burner and the wick-tube. Fig. 5 is a vertical section at right angles to 35 Fig. 1, without the chimney.

The screw-base a of the burner is of usual character, except that the opening for the lower end of the wick-tube b is not straight, but it is curved into an elliptical form, the 40 lower end of the said wick-tube corresponding thereto, but the upper end of the said wick-tube is straight.

The wick-raising wheels c occupy the concave side of the wick-tube and their teeth pass 45 through slots in the side of the wick-tube. The ratchet-cap d covers the wick-raisers, and the perforations at 1 1 in the sides of the base a and 2 2 in the top of the ratchet-cap allow a circulation of air through the base of the 50 burner, to keep the same cool. This wick-tube

allows of the use of a broad wick with a small collar, because it is in a curved form where it passes through the screw-collar.

The wick-tube guide f is made cylindrical at its lower end to rest upon the ratchet-cap d , 55 and the sides are inclined toward its upper end, so as to be wedge-shaped and come up around the wick-tube at its upper end. There are, however, air-openings between the top edges of the wick-tube guide and the wick-tube, so that the light may not be extinguished by placing the guide over the wick-tube or by removing it. The lugs 4 on the ratchet-cap enter the notches in the bottom part of the wick-tube guide, to prevent injury to the wick-tube in screwing the burner to the fountain. 65

The foraminous air-distributer h extends from the base of the wick-tube guide to the bottom of the chimney-holder k . Said chimney-holder is not round, square, oblong, or 70 formed with hooks, as have heretofore been used, but it is an ellipse, so that its ends are nearly the same distance from the edges of the wick that the sides of the elliptical chimney-holder are from the sides of the wick, whereby 75 there is a uniformity in the air-spaces around the wick, and each part of the chimney-holder is nearly the same distance from the flame, so as to equalize the temperature and the action of the air. This chimney-holder k has a clamping-screw, 12, or similar fastening for the chimney. 80

The bottom part of the air-distributer around the wick-tube guide is flat and elliptical, of a size approximating to that of the elliptical 85 chimney-holder, to form a base on which the parts rest when removed, and from this flat portion the air-distributer curves upward and outward to the chimney-holder.

The deflector l is of an elliptical form at the 90 base; but the same is smaller than the chimney-holder, so as to allow the chimney to rest upon the flat flange 3 of the deflector, and this flange is perforated to allow a current of air to pass between the deflector and the chimney. 95

The deflector is an elliptical dome in its shape, with a flame-slot running along the top in the direction of the greatest length of the deflector, and the slot is widened at 14 14 at each side of the central portion, the object of 100

this being to prevent the current of air from acting too powerfully at each side of the center of the flame, and thereby rendering it a blue color.

5 The chimney has an elliptical base that passes into the chimney-holder, and the bulb of the chimney is widest in the same direction as the flame spreads, and the sides of the chimney are contracted so as to be concave at 5, 10 as seen in Fig. 2, and the top of the chimney is elliptical and of about the same size as the base of the deflector. In practice I find that a chimney of this shape operates more satisfactorily than the bulbs with straight, flat, or 15 convex sides, because the flame is rendered nearly uniform in thickness and brilliancy, and it is rounded at the top edge, so as not to smoke, and is of nearly uniform brilliancy throughout.

20 I am well aware that the elementary features of my burner have been in existence before. I have combined together devices that form a new and superior burner. So, also, of the chimney. Different portions thereof resemble

other chimneys; but no chimney has before 25 been made having all the peculiarities set forth. Hence said chimney is novel, and it possesses special features of utility, as described.

I claim as my invention—

1. The lamp-chimney having an elliptical 30 base and a bulb the sides of which are flattened and concave, as at 5, as and for the purposes specified.

2. The combination, in a lamp-burner, of a 35 wick-tube, a wick-raiser, a ratchet-cap, a wick-tube guide, a foraminous air-distributer, that is united to the wick-tube guide and forms an elliptical base that is flat, and then extends upward to the chimney-holder, an elliptical deflector, and an elliptical chimney-holder, substantially as set forth.

Signed by me this 30th day of June, 1879.

H. W. HAYDEN.
